UNITED STATES PATENT OFFICE.

IDA MAY GUTHRIE, OF CARTHAGE, ILLINOIS.

CONVERTIBLE SUPPORT FOR BOOKS, &c.

1,009,508.

Specification of Letters Patent. Patented Nov. 21, 1911.

Application filed July 12, 1911. Serial No. 638,169.

To all whom it may concern:

Be it known that I, Ida M. GUTHRIE, a citizen of the United States, residing at Carthage, in the county of Hancock and State of Illinois, have invented certain new and useful Improvements in Convertible Supports for Books, &c., of which the following is a specification.

The present invention embodies an improved support adapted for special adjustment, and to be collapsed, and is designed particularly for use in holding a book convenient for reading by a person confined to a bed or sitting in a chair. The book supporting means employed is of such construction as to permit of ready collapsing when it is not desired to use the device, and furthermore the parts are so adjusted that the support may be converted into a table for use in other ways than that above referred to.

For a full understanding of the present invention, reference is to be had to the following description and to the accompanying drawings, in which—

Figure 1 is a perspective view of the invention with the parts adjusted for use as a book support; Fig. 2 is a vertical sectional view, certain parts omitted and others shown in elevation; Fig. 3 is a front elevation of the book supporting member and the horizontal supporting bar on which it is mounted, the latter being shown partly in section; Fig. 4 is a view showing the book support collapsed; Fig. 5 is a sectional view taken approximately on the line 5-5 of Fig. 1;

Throughout the following detail description and on the several figures of the drawings, similar parts are referred to by like reference characters.

Specifically describing the invention and the advantageous operation and uses thereof. A denotes a pair of hollow standards having suitable supporting legs B at their lower ends and receiving at their upper ends the adjustable sections C, the latter comprising vertical portions movable in the hollow portions of the standards A, said parts having registering openings in which pins 45 are adapted to be received to hold the parts at desired vertical adjustments. The sections C of the standards A have lateral arms at their upper ends, which are adapted to be received in the hollow portion of the horizontal bar E. Set screws 1 are carried by the member E and permit of adjustment

of the members A and C toward and from one another, as well as affording a means permitting rotation of the bar E on the arms of the sections C to vary the inclination of the book support F. The book support F comprises a base plate 2, a supporting plate 3, and the side plates 4. Projecting downwardly from the base plate 2 is a post or stud 5 which is mounted in a tubular bearing 6 projecting upwardly from the horizontal bar E. The parts 5 and 6 permit of rotative movement of the book rest F in an obvious manner with respect to the main support carrying said book rest. The side plates 4 are provided with a series of notches 4' at intervals along their front edge portions and a transverse adjusting and locking rod 7 is adapted to be engaged in corresponding notches 4' to hold the book supporting plate 3 at a suitable inclination as desired. The plate 3 has a suitable rest flange 3' at its lower edge and the locking rod 7 is formed at its opposite extremities with heads adapted to engage with the outer surfaces of the sides 4 to prevent accidental displacement of the latter from operative positions in respect to the supporting plate 3. The side plates 4 are hinged at their lower edges, as shown at 8 to the base plate 2 whereby the side plates may be lowered into positions resting upon one another, as shown in Fig. 4, and the plates 3 also move downwardly so as to rest upon the uppermost side plate in collapsing the book rest 90 to place the same out of use or for utilizing the plate 3 as a sort of table. The plate 3 is pivoted at its lower front edge portion to ears 9 at opposite sides of the base plate 2 and the side plate 3 has a spring catch 95 10 projecting from its rear side to engage with the rear edge of the plate 2 to hold the members 3 and 4 in collapsed positions.

Under some conditions, in order to obtain a larger table surface, it may be desired to 100 adjust the side plates 4 so that they project outwardly from the base plate 2, as shown in dotted lines in Fig. 3, whereupon the plates 4 will be supported on the lugs 11 and thus maintained in horizontal positions.

The standards A may be moved toward or from one another and properly adjusted according to the width of a bed or chair adjacent to which the device may be positioned 110 and the book rest may of course be raised or lowered to a desired adjustment by rea-

son of the mounting of the sections C on the standards A.

The invention is very simple in its construction and the adjusting means employed are susceptible of ready manipulation to accomplish the desired results.

Having thus described the invention, what is claimed as new is:

1. In an adjustable support of the class described, the combination of a book rest comprising a base plate, side plates, a supporting plate, means adjustable on the side plates for holding the supporting plate at a predetermined adjustment, connections between the side and supporting plates and the base plate permitting the former to be collapsed so as to rest upon the base plate, and a main support for the book rest aforesaid.
2. In an adjustable support of the class described, a book rest consisting of a base plate, side plates pivotally connected with the base plate and movable into positions resting on the base plate or extending outwardly therefrom in substantially horizontal positions for use as table members, a supporting plate movably mounted on the base plate, and means normally holding the side plates in vertical positions and at the same time holding the supporting plate at a desired adjustment.
3. In an adjustable support of the class described, a book rest consisting of a base plate, a book supporting plate pivoted to the front portion of the base plate and adapted to fold downwardly thereon, side plates pivoted to the side edge portions of the base plate and also adapted to fold downwardly thereon, and means adjustable on the side plates for holding the book supporting plate in a predetermined position.
4. In an adjustable support of the class described, a book rest consisting of a base plate, a book supporting plate pivoted to the front portion of the base plate and adapted to fold downwardly thereon, side plates pivoted to the side edge portions of the base plate and also adapted to fold downwardly thereon, and means adjustable on the side plates for holding the book supporting plate in a predetermined position, and means pro-

jecting from the base plate for supporting the side plates in horizontal positions for use as table members.

5. In an adjustable support of the class described, a book rest comprising a supporting member, a base plate mounted thereon, a book supporting plate pivoted to the front edge portion of the base plate, side plates hinged at their lower edges to the side edge portions of the base plate and adapted to fold downwardly upon the latter, a catch carried by the book supporting plate to engage the base plate to hold the book supporting plate in collapsed position over the downwardly folded side plates, said plates being provided with a series of notches, and a locking rod adapted to be seated in corresponding notches of the side plates, and to hold the book supporting plate in adjusted positions.

6. In an adjustable support of the class described, a book rest comprising a supporting member, a base plate mounted thereon, a book supporting plate pivoted to the front edge portion of the base plate, side plates hinged at their lower edges to the side edge portions of the base plate and adapted to fold downwardly upon the latter, a catch carried by the book supporting plate to engage the base plate to hold the book supporting plate in collapsed position over the downwardly folded side plates, said plates being provided with a series of notches, and a locking rod adapted to be seated in corresponding notches of the side plates and to hold the book supporting plate in adjusted positions, and heads at opposite ends of the locking rod preventing accidental outward movement of the side plates, the base plate having lugs extending from its opposite side edges to form supporting members for the side plates when the latter are moved outwardly into substantially horizontal positions.

In testimony whereof I affix my signature in presence of two witnesses.

IDA MAY GUTHRIE.
